(57) **CLAIM**

The ornamental design for “panel shaped data display,” as shown and described.

DESCRIPTION

FIG. 1 is a perspective view of a panel shaped data display in an open position in accordance with my new design;

FIG. 2 is a front elevation view thereof;

FIG. 3 is a rear elevation view thereof;

FIG. 4 is left-side elevation view, the right-side elevation view being identical thereto;

FIG. 5 is a top plan view thereof;

FIG. 6 is a bottom plan view thereof;

FIG. 7 is a perspective view of the panel shaped data display in a closed position;

FIG. 8 is a front elevation view thereof;

FIG. 9 is a rear elevation view thereof;

FIG. 10 is left-side elevation view, the right-side view elevation being identical thereto;

FIG. 11 is a top plan view thereof; and,

FIG. 12 is a bottom plan view thereof.

The subject matter shown in dashed lines is for reference purposes only, and forms no part of the claimed invention.
